John W. Lightburn

WITNESS:

UNITED STATES PATENT OFFICE.

ROBERT W. LIGHTBURN, OF GANS, PENNSYLVANIA.

SAFETY DEVICE.

Application filed April 12, 1923, Serial No. 631,631. Renewed January 14, 1924.

To all whom it may concern:

Be it known that I, ROBERT W. LIGHTBURN, a citizen of the United States, residing at Gans, in the county of Fayette and State of Pennsylvania, have invented new and useful Improvements in Safety Devices, of which the following is a specification.

This invention relates to a derailing device, the general object of the invention being to provide means whereby the device is drawn along with the car and will be automatically caused to derail the same when the car starts to move rearwardly or down an incline.

While the device is mainly designed for use in mines it will of course be understood that it may be used in other situations.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view showing the device attached to a car and slidably engaging a rail.

Figure 2 is a view showing how the device acts to cause the wheel to leave the rail.

Figure 3 is an enlarged plan view of the device.

Figure 4 is a side view.

Figure 5 is a perspective view of the device.

In these views 1 indicates a base which has vertical flanges 2 at its front end and at its rear end it is formed with a thickened part 3, the front edge of which is beveled, as at 4, in such a manner that when the flange of the wheel strikes this beveled portion the wheel will be deflected through the space 5 between the flange 2 and said part 3. The front edge of the base is provided with a notch 6 for receiving the flange of the wheel. Pins 7 are carried by the sides of the part 3 and the upper ends of the bars 8 are pivoted to these pins. These bars are designed to ride over the track, as shown in Figure 1, when the device is pulled forwardly but if the car should start to slip back rearward movement of the device is

prevented by the pointed ends 9 of these bars entering the road bed or engaging the ties. Pins 10 are carried by the ends of the member 3 and these pins are engaged by eyes formed in the vertical part 11 of an attaching device 12, the horizontal part 13 of this device being adapted to be connected with a part of the car. Ribs 14 are formed on the bottom of the device for engaging the rail.

From the above it will be seen that when the device is attached to the rear end of the last car of the train it will be pulled along the track, the bars 8 simply riding over the ties or roadbed as they are loosely connected at their upper ends with the device. If a cable should break or something else happened that would cause the train to start to slide down the track the eyes in the attaching device 12 would leave the pins 10, thus freeing the device from the car and the lower ends of the bars would engage the roadbed or the ties so as to prevent movement of the device. Thus the wheel would ride up on the base and when it struck the inclined end of the member 3 it would be deflected through the space 5 and thus the car would be derailed. The device can be made to throw the car to either the right or left hand side of the track. This device will not interfere with the cable rollers and this device will derail the car soon after it starts to run down the incline.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A derailing device comprising a base having a raised portion at its rear provided with an inclined front edge to deflect the wheel, means pivotally connected with the rear part of the device for riding over the track when the device is pulled forwardly but will engage a track and stop the device when the same starts to move rearwardly and means for connecting the device to a car in such a manner that it will be dragged by the car but will become separated therefrom when the car starts to move rearwardly. 105

2. A derailing device comprising a base having a raised portion at its rear provided

- 2
- with an inclined front edge to deflect the wheel, means pivotally connected with the rear part of the device for riding over the track when the device is pulled forwardly but will engage the track and stop the device when the same starts to move rearwardly, means for connecting the device to a car in such a manner that it will be dragged by the car but will become separated therefrom when the car starts to move rearwardly, such means consisting of a projection on the rear of the device and an attaching member having an eye for slipping over the projection.
- 15 3. A derailing device of the class described comprising a base, a rail engaging groove in the bottom thereof, flanges at the front ends of the sides of the base, a raised part at the rear of the base having its front end inclined, a projection at the rear of the
- 10
- 20

raised part, an attaching device having an eye therein for engaging the projection and a bar having its front end pivoted to one side of the raised part so that its lower end will engage the track.

- 25 4. A derailing device of the class described comprising a base, a rail engaging groove in the bottom thereof, flanges at the front ends of the sides of the base, a raised part at the rear of the base having its front end inclined, a projection at the rear of the raised part, an attaching device having an eye therein for engaging the projection, a bar having its front end pivoted to one side of the raised part so that its lower end will engage the track, said base having a notch in its front end for receiving the wheel flange.

30 In testimony whereof I affix my signature.

ROBERT W. LIGHTBURN.
